UNITED STATES PATENT OFFICE

92,270

DESIGN FOR A COCKTAIL CART

Fred Schmid, Chicago, Ill., assignor to Albert Pick Co., Inc., Chicago, Ill., a corporation of Illinois

Application February 16, 1934, Serial No. 50,751

Term of patent 3½ years

To all whom it may concern:

Be it known that I, FRED SCHMID, a citizen of the United States, residing at Chicago, in the county of Cook and State of Illinois, have invented a new, original, and ornamental Design for Cocktail Carts, of which the following is a specification, reference being had to the accompanying drawing, forming a part thereof: wherein

I claim:

The ornamental design for a cocktail cart substantially as shown.

Signed at Chicago this 9th day of February, 1934.

FRED SCHMID.
